(57) **CLAIM**

The ornamental design for a front portion of a disk drive bracket, as shown and described.

DESCRIPTION

FIG. 1 is a perspective view of a front portion of a disk drive bracket; and,

FIG. 2 is a frontal view of a front portion of a disk drive bracket.

The broken line illustration in FIG. 1 of other portions of a disk drive bracket is not part of the claimed design. Since the ornamental design of only the front portion of a disk drive bracket is claimed, other views (e.g. rear, top, bottom, and sides) of the disk drive bracket are not shown.
